Filed Apr. 10, 1958, Ser. No. 727,657
2 Claims. (Cl. 4-172)

The present invention relates to a swimming pool construction and more particularly to a swimming pool surround and associated cabana.

The swimming pool associated with a residence has become a national feature. Frequently, however, such pools are either extremely expensive or, on the other hand, are of such flimsy construction as to make them uneconomic.

The object of the present invention is to provide a novel swimming pool structure of a simple and inexpensive, and yet of structurally sound, nature which may be installed either above or below ground level.

Another object thereof is the provision of such a structure which incorporates a platform or cabana auxiliary structure.

Still another object thereof is a swimming pool surround which while adaptable to metal construction is nevertheless also easily constructed of wood, and in such a manner as to resist deterioration by action of the elements, water seepage and the like.

A still further object thereof is the provision of a swimming pool surround which may be adapted to a variety of shapes and yet retain its structural integrity under adverse conditions.

Yet another object thereof is the provision of reinforcing and buttressing means for a pool structure which, while effective, are nevertheless simple and economical.

The above and other objects are attained in the preferred form by means of constructing the four walls of a rectangular pool enclosure of stacked rails separated by spaces positioned at regular intervals along the walls, some of the spaces being of graduated length in the direction outwardly normal to the walls and a greater length towards the bottom than the top of said walls so as to furnish buttresses to support the walls against the outward thrust of water contained within the pool enclosure.

An added feature may be a raised platform or cabana structure, the lower side walls of which are interleaved with the side walls of the pool enclosure and the floor of which may likewise comprise an alternately horizontally spaced arrangement of rails separated by spaces.

Other objects and a fuller understanding of the present invention may be had by referring to the following detailed description and claims, taken in conjunction with the accompanying drawings which illustrate preferred embodiments thereof, it being understood that the foregoing statement of the objects of the invention and the brief summary thereof is intended to generally explain the same without limiting it in any manner.

FIG. 1 is a perspective view of a pool structure embodying the present invention, portion being shown in dotted outline and the coping and pool liner being omitted.

FIG. 2 is an enlarged plan view taken along lines 2-2 of FIG. 1.

FIG. 3 is a sectional view taken along lines 3-3 of FIG. 2.

FIG. 4 is a sectional view taken along lines 4-4 of FIG. 2.

FIG. 5 is a sectional view taken along lines 5-5 of FIG. 2.

FIG. 6 is a plan view of section of the cabana floor adjacent to line 6-6 of FIG. 1.

2

FIG. 7 is a sectional view taken along lines 7-7 of FIG. 6.

FIG. 8 is a plan view of another embodiment of the pool structure.

5 FIG. 9 is a fragmentary side elevation of the cabana structure illustrating the arrangement of the steps and door opening in one of the side walls.

Referring now to the drawings and to the preferred form of the invention shown in FIGS. 1-7, it comprises a rectangular pool enclosure or surround 10 at one end of which there is incorporated a raised cabana structure 11. The four side walls 12, 13, 14 and 15 of the pool enclosure 10 each comprise vertically stacked, elongated wall elements or rails 16 separated vertically by spacer blocks 17, both rails and blocks being preferably of wood. Spacer blocks 17 may be positioned at convenient horizontal intervals. Vertically aligned bores 19 in rails 16 and spacer blocks 17 provide an elongated bore through which bolt 19 extends, the uppermost and lowest rails 15 having recesses 20 and 21 in which the head of bolt 19 and the corresponding nut 22 are seated. The blocks and rails are tightly compressively secured when the nut is tightened. If pool surround 10 be deemed to have the dimensions of 32' x 16' then said spacer blocks would be located at intervals of 4 feet. For such a surround, rails 16 may be of 3" x 1 1/2" lumber and wall height may be 42". As shown in FIGS. 1, 2 and 3, there extends outwardly from side walls 12 and 13 buttresses 18 having a section in the form of truncated triangles. Each buttress 18 is formed of spacer blocks 17, 17", 17''' etc. which increase in length from top to bottom and extend normally outwardly from said rails. The outermost ends 23', 23" and 23''' etc. of said blocks are bevelled in a parallel plane as are the corresponding ends of spacer elements 24 positioned between said blocks proximate their outer ends. The outer portions of said blocks and elements are provided with angled aligned bores parallel to said bevelled ends, through which bolt 19 extends and is tightened by nut 22 to secure said outer portions. Such buttresses 18 prevent the side walls from bulging or giving way under lateral water pressure when the pool is filled.

At the corners, the side walls interlock, i.e. the rails forming each wall alternate with the rails of the other (see FIG. 5). Hence no spacers are needed at such places. However, the rails are apertured at corners to form bores in which bolt 19 and its matching nut 22 are employed to tightly secure the wall elements to each other. Rails 16 may overhang the corners to form corner tabs 25 either for decorative purposes or for another purpose explained below.

When the pool enclosure is erected above ground tie straps 26 made of steel, aluminum, wood or the like may extend between opposing side walls 12 and 13 to afford additional reinforcement means to resist lateral water pressure. They are not needed when the surround is positioned in an excavation since concrete will then be poured about buttresses 18 to anchor them.

60 To complete the pool a durable watertight liner 27 of polyethylene or other suitable material is spread to extend between the side walls and along the inner surface of the same being secured to the top rails 16 thereof by a coping 28 which may be bolted or otherwise fastened to said top rails. Additional conventional anchorage of the bottom of said pool liner or of the side thereof to said side walls may be provided. A wall ladder 29 may also be provided.

65 The opposed side walls 12' and 13' of cabana 11 may be mere extensions of side walls 12 and 13, respectively. End wall 15' of cabana 11 will then be interlocked with said side walls in the same manner as walls 14 and 15 of the pool surround. However, since it is desired to

make the floor or platform of said cabana of the same type of rail construction as previously described with reference to the side walls (except, of course, that they are horizontally rather than vertically spaced) it is convenient to use broader side rails 30 (see FIGS. 6 and 7) as wall elements of walls 15 and 15' immediately below the level of floor rails 31 of said floor or platform to provide support thereto.

To secure floor rails 31 together they are similarly separated by horizontal spacers 32 which together with said rails are apertured proximate their ends to form a bore 19' through which bolt 19 extends and is tightened by nut 22. The end floor rails may contain recesses 33 and 34 to permit the countersinking of the bolthead and said nut. To permit the use of the same size bolt 19 as is employed in vertically securing side rails 16 said floor rails 31 may be secured in a number of different sections which may merely rest on broad side rails 39 or be secured thereto (by conventional means not shown).

Should it be desired to erect a cabana roof over said floor or platform, conventional corner posts 35 may be erected and secured to the structure described and roof elements (not shown) may likewise be erected between corner posts 35. A set of steps 36 may be positioned along side wall 12' to permit easy access to the cabana platform. To further increase the utility of said steps they may be connected to the top of said wall by a piano hinge 37 so that when the pool is not in use steps 36 may be pivoted away from the ground and upon said platform to make undesired access thereto more difficult. Alternately, when said cabana is constructed with side walls between posts 35, a door opening D will, of course, be provided in the side wall S at the head of steps 36 which may then be closed by pivoting wall 38 of said steps to a closed-door position flush with the trim of the door opening D and locking the same in such position by conventional door-locking means.

In FIG. 8 a modified form of the present invention is illustrated. Here the pool surround is hexagonal rather than rectangular. Side walls 39 of said surround are formed and connected in the same manner as side walls 12, 13, 14 and 15 of the first embodiment shown. Here, however, the second use for end tabs 25 is portrayed. Thus said ends are connected by tie pieces 40, the end portions of such tabs and pieces being similarly apertured to permit their connection by bolts 19 screwed home into nuts (not shown). Such means add additional rigidity to the surround.

A cabana 41 may be added to the pool surround in the same manner as previously described except that in this instance it may be desired to mount the cabana side walls 12' and 13' to tabs 25 of the side wall 39 forming the front of the lower cabana structure.

It should be pointed out that the structures described are particularly well adapted to hygienic installations. The alternate rail walls permit air to circulate beneath a cabana and therefore enable the evaporation of moisture which falls to the ground through the slatted floors of the cabana. In this connection the fact that the floors of the cabana are slatted are themselves an advance in that water does not collect upon the cabana floor making it slippery, but falls through the same, the floor drying out quickly after use by bathers. Similarly, the side walls of the pool surround dry out quickly after wetting by reason of splashed water or by the elements.

In addition, the structure shown may be readily disassembled so that should an owner in a temperate cli-

mate desire to store the same during the cooler portions of the year he may easily take the structure apart. Similarly, the structure may be easily reassembled the next season. Again, the structure permits the use of a variety of pool liners which are readily replaceable.

The structural rigidity of the pool surround is vastly enhanced by the incorporation of the feature which includes coping 28. Coping 28 may be made of elongated boards which then serve to link, when properly affixed to top rail 16, parallel sections of the rail which interlock. This adds considerably to the resistance to lateral deformation by water pressure.

Manifestly, if it is desired to still further reinforce the structure then instead of a single coping 28 such as the board shown in the drawings, a set of vertically superimposed boards may be affixed atop the fence as shown. This will then serve as additional reinforcement.

Should the user desire to deepen the pool at one end all that is necessary to do is to make an excavation at such end and in self-evident fashion, by causing the liner to cover the depression and extend over the edges of the pool surround, a portion of the pool suitable for diving may be formed.

Although the present invention has been described with a certain degree of particularity, it is understood that the present disclosure has been made only by way of example and that numerous variations may be employed without transcending the scope of the invention as hereinafter claimed.

30 What is claimed is:

1. A pool surround including a continuous fence defining an enclosure said fence being regularly polygonal in outline and including linear sections of vertically spaced rails, the rails of each linear section alternating 35 with the rails of the adjacent linear sections and extending beyond the point of contact therewith to form extending corner tabs and rigid tie pieces affixed to and connecting marginal portions of said corner tabs.

2. In a pool structure, a plurality of upwardly extending 40 retaining walls connected together in fixed relation and being arranged for embracing pool lining means disposed within the confines of said walls, a pair of said walls being spaced from each other and provided with extensions extending outwardly from another of said walls 45 and connected together at their outer ends, a cabana structure associated with said extensions and including a raised platform mounted adjacent said last mentioned wall and between said extensions, sides extending upwardly from said platform, a roof connected to said sides 50 and mounted over said platform, at least one of said sides having a door opening, and a flight of downwardly extending steps pivotally connected to said platform in front of said opening and capable of being pivoted into said opening for closing the latter.
